(57) **CLAIM**

The ornamental design for flatware set, as shown and described.

DESCRIPTION

FIG. 1 is a perspective view of a flatware set showing my design.

FIG. 2 is a right side elevational view of the flatware set.

FIG. 3 is a left side elevational view of the flatware set.

FIG. 4 is a front elevational view of the flatware set.

FIG. 5 is a back elevational view of the flatware set.

FIG. 6 is a top elevational view of the flatware set.

FIG. 7 is a bottom elevational view of the flatware set.

FIG. 8 is a perspective view of a knife of the flatware set.

FIG. 9 is a left side elevational view of the knife.

FIG. 10 is a right side elevational view of the knife.

FIG. 11 is a top plan view of the knife.

FIG. 12 is a bottom plan view of the knife.

FIG. 13 is a front elevational view of the knife.

FIG. 14 is a rear elevational view of the knife.

FIG. 15 is a perspective view of a fork of the flatware set.

FIG. 16 is a left side elevational view of the fork.

FIG. 17 is a right side elevational view of the fork.

FIG. 18 is a front elevational view of the fork.

FIG. 19 is a rear elevational view of the fork.

FIG. 20 is a top plan view of the fork.

FIG. 21 is a bottom plan view of the fork.

FIG. 22 is a perspective view of a spoon of the flatware set.

FIG. 23 is a left side elevational view of the spoon.

FIG. 24 is a right side elevational view of the spoon.

FIG. 25 is a front elevational view of the spoon.

FIG. 26 is a rear elevational view of the spoon.

FIG. 27 is a top plan view of the spoon; and,

FIG. 28 is a bottom plan view of the spoon.
